(57) **CLAIM**

The ornamental design for an air cleaning apparatus, as shown and described.

DESCRIPTION

FIG. 1 is a front, bottom side isometric view of an air cleaning apparatus;

FIG. 2 is a rear, top side isometric view of the air cleaning apparatus;

FIG. 3 is a front view of the air cleaning apparatus;

FIG. 4 is a rear view of the air cleaning apparatus;

FIG. 5 is a top side view of the air cleaning apparatus;

FIG. 6 is a bottom side view of the air cleaning apparatus;

FIG. 7 is a left side view of the air cleaning apparatus; and,

FIG. 8 is a right side view of the air cleaning apparatus. The evenly dashed broken lines illustrate portions of the air cleaning apparatus that form no part of the claimed design.

1 Claim, 4 Drawing Sheets
